223,596

SYRINGE AND AMPULE WARMER

Charles J. Courtenay, P.O. Box 7182,
Orlando, Fla. 32804

Filed Dec. 8, 1970, Ser. No. 25,578

Term of patent 14 years

Int. Cl. D24—02
U.S. Cl. D83—1

FIG. 1

FIG. 2

FIG. 1 is a perspective view of a syringe and ampule warmer embodying my new design; and

FIG. 2 is a top plan view of the warmer of FIG. 1 having an open lid.

The undisclosed sides are substantially the same as the sides shown.

I claim:

The ornamental design for a syringe and ampule warmer, substantially as shown and described.
